UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNET AND SOLENOID.

1,142,852.

Specification of Letters Patent. Patented June 15, 1915.

Application filed June 6, 1910, Serial No. 565,211. Renewed October 10, 1913. Serial No. 794,517.

To all whom it may concern:

Be it known that I, ARTHUR SIMON, a citizen of the United States, residing at Milwaukee, in the county of Milwaukee and State of Wisconsin, have invented new and useful Improvements in Electromagnets and Solenoids, of which the following is a full, clear, concise, and exact description, reference being had to the accompanying drawing, forming a part of this specification.

My invention relates to improvements in electromagnets, or solenoids.

It is the principal object of my invention to provide an electromagnet, or solenoid which will automatically reduce the amount of current flowing through its energizing winding after the same has responded, but not until the plunger, or movable armature thereof, has reached the full limit of its stroke.

Various other objects and advantages of my invention will hereinafter be clearly and fully set forth.

In order to more fully disclose the nature and characteristic features of my invention, I shall describe the device illustrated in the accompanying drawing which embodies my invention in one form. It should be understood, however, that my invention is susceptible of various modifications and is not limited to the particular embodiment thereof illustrated in the drawing.

In the accompanying drawing, Figure 1 illustrates a solenoid operated switch embodying my invention in its preferred form, the solenoid winding and the stationary plug thereof being shown in section, and Fig. 2 is a view of the auxiliary switch and its operating contacts illustrating a modification of my invention.

The device illustrated in Fig. 1 comprises essentially a magnet frame 3, in which is mounted an electromagnetic winding 4. Within the winding 4 is arranged a longitudinal plunger 5 arranged to engage and seal with a stationary plug 6 suitably secured to the magnet frame and projecting into the upper end of the solenoid winding. Of course, the solenoids may be used for various different purposes. As illustrated, the plunger thereof is provided with a tail

rod 7 upon which is mounted a switch member 8 adapted, when the solenoid is energized, to be moved into an engagement with the stationary contacts 9 and 10. Arranged above the solenoid is an auxiliary switch 12 having a stem 13, of magnetic material, projecting into the stationary plug 6, which is made tubular to receive the same. The auxiliary switch 12 is provided with stationary contacts 14 and 15 and is normally held in engagement therewith by the coil spring 16 surrounding the stem 13 thereof, and bearing against the stationary plug 6. In the present instance, the auxiliary switch is arranged to control a resistance 18, which is short-circuited thereby when said auxiliary switch engages its stationary contacts.

Before describing the operation and functions of the switch illustrated in the drawing, I desire to briefly discuss the conditions existing in the switch heretofore designed to automatically reduce the amount of current flowing through the same. Where it has been desired to accomplish this result, it has been customary to provide a solenoid with an auxiliary switch arranged to control a resistance similar to the resistance 18 which, as will hereinafter be described, is arranged to be connected in series with the solenoid winding. Heretofore, however, it has been customary to operate the auxiliary switch mechanically as the plunger of the solenoid approaches the limit of its movement. Ordinarily the auxiliary switch has been arranged to be operated by the plunger itself. Thus in order to secure operation of the auxiliary switch it has been necessary to so adjust the same that it will be operated just prior to the sealing of the plunger with the stationary plug. Hence, the protective resistance has necessarily been inserted in circuit with the solenoid winding before its plunger has actually sealed with the stationary core. Ordinarily the protective resistance is only required where over excitation is required to operate the solenoid plunger owing to its load. Hence, if the protecting resistance is inserted in series with the solenoid winding before the plunger has firmly sealed with the stationary plug, either the plunger will not be attracted to the full extent of its movement,

or else it will only be finally sealed with the stationary plug after objectionable vibrating, or telegraphing thereof. This vibrating, or telegraphing is due to the premature reduction in the magnetic attraction by the insertion of the protective resistance.

It is to avoid the decrease of the magnetic pull of the solenoid, before the plunger is moved to its full extent, that my invention is particularly aimed. I shall now describe the operation of the switch illustrated in the drawing to show that the same will accomplish this result.

Let it be assumed that current is supplied to the solenoid winding 4 from supply lines 15 20 and 21, the circuit of said solenoid winding being controlled at will by a control switch 21^a. With the parts in the position illustrated, upon closure of switch 21^a the 20 circuit is closed as follows: From main line 20, through switch 21^a, by conductor 22, through auxiliary switch 12, by conductor 23, through the solenoid winding 4, to conductor 21. The solenoid winding is thereupon energized tending to draw its plunger 25 upwardly. The spring 16 is so adjusted as to prevent the magnetic attraction of the auxiliary switch until the solenoid plunger 5 has sealed with the stationary plug 6. This is made possible by the fact that during 30 the movement of the solenoid plunger, the energizing current and consequently the magnetism is maintained below normal value due to self-inductance and only reaches maximum strength when the plunger 35 seals with the stationary core. While the magnetism of the solenoid remains below normal, only a comparatively few magnetic lines of force stray through the stem 40 of the auxiliary switch with the result that the spring 16 will overcome the slight magnetic pull thus exerted upon the auxiliary switch. When, however, the plunger seals with the stationary plug the current and 45 the magnetism rise to the maximum strength thereby saturating the plug with magnetic lines of force, a sufficient number of said lines of force now passing through the stem of the auxiliary switch to attract the same 50 against the opposition of the spring 16. In other words, the stem of the auxiliary switch in effect forms an auxiliary plunger for the solenoid winding, which owing to the arrangement thereof in the stationary plug 55 and further owing to the resistance of the spring 16, will not be attracted until the main plunger 5 has been moved to its full extent, thereby sealing with the stationary plug 6. As soon as the auxiliary switch 12 60 is drawn away from its stationary contacts, the protective resistance 18 is inserted in series with the solenoid winding, thereby reducing the flow of current through said winding to a safe value. However, even 65 with the resistance 18 in circuit a sufficient

amount of current is allowed to pass through the solenoid winding to maintain the plunger 5 in raised position. The auxiliary switch will be maintained in its retracted position until the solenoid winding 70 is deenergized, whereupon the spring 16 will again move the same into engagement with its stationary contacts.

In Fig. 2, the stationary contact 15 of the auxiliary switch is connected to conductor 22, through a coil 25 surrounding said contact. Likewise the contact 14 of the auxiliary switch is connected to conductor 23, through a coil 26 similar to the coil 25. The coils 25 and 26 perform a twofold function. In the first place, they create a magnetic flux which tends to magnetically hold the auxiliary switch 12 in engagement with the contacts 14 and 15. Of course, this magnetic attraction of the auxiliary switch opposes the pull of the solenoid winding 4 and, therefore, must be taken into account in adjusting the spring 16, to insure the magnetic attraction of the solenoid 4 overcoming the combined opposition of the spring and the magnetic attraction of the coils 25 and 26, at the proper time. The auxiliary switch being magnetically attracted to the contacts 14 and 15 will, when finally attracted by the solenoid winding 4, leave said contacts with 95 a snap action, thereby giving a quick break of the short-circuit around the resistance 18. Secondly, the coils 25 and 26 will create a magnetic flux which will extinguish any arcs drawn between the auxiliary switch and the 100 stationary contacts upon separation thereof.

As before set forth, my invention is susceptible to various modifications and, therefore, the structure illustrated and heretofore described should not be considered as 105 limiting the scope of my invention.

Having thus described my invention, what I claim as new and desire to secure by Letters Patent, is:

1. A solenoid having a main plunger and 110 an auxiliary plunger, the latter being attracted only after a predetermined movement of the former and controlling means for said solenoid actuated by said auxiliary plunger.

2. The combination with an electromagnet having a stationary pole piece and a movable magnetically attracted part adapted to seal with said pole piece, of a switch having a magnetic portion projecting into said pole piece and arranged to be electromagnetically moved to operate said switch to reduce the flow of current through said electromagnet, and means for preventing operation of said auxiliary switch until said movable magnetically attracted part has sealed with said pole piece.

3. The combination with a solenoid having a stationary core and a movable plunger arranged to seal with said core, of an auxil-

- 5 iary switch having a magnetic portion projecting into said core and forming an auxiliary plunger for said solenoid, said auxiliary plunger being adapted to be attracted after said first mentioned plunger has sealed with said stationary core to operate said switch to reduce the flow of current through the solenoid winding.
- 10 4. The combination with a solenoid having a stationary core and movable plunger arranged to seal with said core, of a switch having a magnetic portion projecting into said core and forming an auxiliary plunger for said solenoid, said switch being adapted when operated to reduce the flow of current through the solenoid winding, and means for preventing the attraction of said switch until said plunger has sealed with said stationary core.
- 15 20 5. The combination with a solenoid having a stationary core and movable plunger arranged to seal with said core, of a switch having a magnetic portion projecting into said core and forming an auxiliary plunger for said solenoid, said switch being adapted when operated to reduce the flow of current through the solenoid winding, and a spring interposed between said switch and said stationary core for preventing the attraction
- thereof by said solenoid until said plunger has sealed with said stationary core.
6. The combination with an electromagnet having a movably magnetically attracted part, of a switch adapted to be magnetically attracted by said magnet to reduce the flow of current therefrom after the movable magnetically attracted part has reached the full limit of its movement, an electromagnetic means tending to hold said switch in engagement with its stationary contacts.
7. The combination with an electromagnet having a movable magnetically attracted part, of a switch adapted to be magnetically attracted by said magnet to reduce the flow of current therethrough, after the movable magnetically attracted part has reached the full limit of its movement, and electromagnetic windings provided with pole pieces forming the stationary contacts of said switch.
- 40 45 50 In witness whereof, I have hereunto subscribed my name in the presence of two witnesses.

ARTHUR SIMON.
